UNITED STATES PATENT OFFICE.

FRITZ MAISENBACHER, OF PFORZHEIM, GERMANY.

PROCESS OF MAKING HOLLOW SOLDERED CABLE AND CURB CHAINS AND RING-PLATTINGS OF PRECIOUS METAL.

1,145,429.

Specification of Letters Patent.

Patented July 6, 1915.

Application filed August 6, 1913. Serial No. 783,421.

To all whom it may concern:

Be it known that I, FRITZ MAISENBACHER, a subject of the German Emperor, and resident of Pforzheim, Germany, have invented 5 certain new and useful Improvements in Processes of Making Hollow Soldered Cable and Curb Chains and Ring-Plattings of Precious Metal, of which the following is a specification.

- 10 In the manufacture of jewelry, most of the precious metal chains are made hollow for economic reasons, as such of solid precious metal are of course rather expensive. Hollow chains could, however, hitherto be 15 made by hand only, and that of rather strong wires. For, hollow wire cannot be bent without losing its shape, for which reason it must be provided with a core of base metal. Thus, it was necessary to coat 20 a wire of iron, brass or other base material with a thin strip of precious metal, so that on the whole core a uniform open longitudinal seam of a certain extent was left. This seam has the purpose to allow the entrance 25 of the acid, which effects the dissolution and removal of the inner wire after formation of the chain links. The wire thus prepared is then wound in a spiral fashion on a round, oval or similarly shaped spindle, 30 of which the cross-section corresponds to the inner width of the chain links to be formed, the longitudinal slot being always placed by hand upon the spindle. Thereupon, this spiral is sawed open in longitudinal 35 direction, so that it is divided into single rings with oppositely directed ends. These rings are, by hand, entangled to form chains, of which the joints are singly soldered and which may be converted by twisting into 40 curb chains. The chain thus prepared is then boiled in an acid dissolving the inner core, so that the empty hollow links only are left.

The present invention, which is herein- 45 after described and illustrated in the accompanying drawing, replaces the whole hand-work by a mechanical process.

Figure 1 is an elevation of a machine used 50 in connection with the process, while Figs. 2 and 3 show, on a larger scale, elevations of the wires prepared for this purpose.

On a wire of iron, brass or other base metal, a seamless cylindric shell of precious metal is welded or drawn in a way known 55 in the art, whereupon the wire is straight-

ened and introduced, by means of the reciprocating slide *b*, into the machine, first into the carrier *a*, of which the very narrow wire guide secures an advance of the wire in straight direction without lateral turning. The slide *f*, which moves behind the cutter *d* by operation of a lever *i*, presses in its position of rest, by means of screws *e*, *e'*, against the upper jaws *h*, *h'*, which are adjustable in their position of height on the pins *g*, *g'*, and arrest the wire in its position. Thereupon, the cutter *d*, which is guided between the screws *e*, *e'*, in a slot of the plate *k*, descends and cuts a longitudinal slot or opening *m* (Fig. 2) into the 60 outer shell of the wire exactly at the highest line of its circumference. The cutter may have a horizontal, oblique or round cutting edge. In case of a solder-cored wire being employed, the openings must not be 65 too deep in order not to reach to the solder-core but to the base metal layer only inserted in this case between the solder-core and the outer shell of precious metal, as otherwise, if the openings would also be cut in said base metal layer, when soldering the liquid solder would penetrate the openings and again close the same entirely, so that the intended object is not obtained. The longitudinal slot remains during the further 70 movement of the wire through the slide *b* always upwardly directed and receives thus upon the formation of the link its place at the inner circumference of the closed chain link. The length of the longitudinal slot 75 is preferably somewhat shorter than each advance of the wire, it being so located in the precious metal shell that it lies exactly in the middle between the two cut-off ends 80 of the wire, which cutting off is effected by 85 the cutter *n*. The longitudinal slot does thus not extend over the whole length of the link wire but to a short distance from both ends only, so that the cross-sections at these 90 ends of the shell remain closed. The wire 95 thus prepared is then led beneath the cutter *n* toward the abutment *o* and formed in a way known in the art into links, which are 100 closed by the joiner *q*. The soldering of the chain is effected automatically in any appropriate way. The chain is then, as in the 105 above-described hand-operated process, exposed to the action of hot acid, which penetrates the interior of the links through the longitudinal slot therein, and, if necessary, 110

agitated in this bath by a mechanical contrivance in order to accelerate the dissolving process of the base metal core. This will, however, hardly be necessary, for since 5 the acid can enter the slot from above and leave the same at the bottom and this circulation happens automatically owing to the weight of the acid increasing with the metal dissolution, the latter is effected in a 10 few hours without assistance by hand.

The longitudinal slot, which extends almost over the whole length of the link, can be replaced by a plurality of openings 15 (Fig. 3) arranged at equal distances from each other in a straight line.

What I claim is:

1. In a process of making hollow soldered cable, curb and other chains and ring plat- 20 tings of precious metal from a wire consist-
ing of a core of base metal with a seam- less precious metal shell drawn or welded upon the same, successively advancing the wire, providing the latter at those places,

which upon formation of links assume the innermost position therein, with openings, 25 and forming then links from the wire, substantially as and for the purpose set forth.

2. In a process of the kind described, pro-
viding a core of base metal with a seamless precious metal shell drawn or welded upon 30 the same and cutting, sawing, shaping or
boring into the latter at those places, which upon formation of links assume the inner-
most position therein, and between the ends of the links to be formed short openings, 35 while leaving the ends of the links uncut by
said openings, substantially as and for the
purpose set forth.

In testimony whereof I have hereunto set
my hand in the presence of two subscribing 40
witnesses.

FRITZ MAISENBACHER.
